UNITED STATES PATENT OFFICE.

CARL CHARLES, OF ROSEDALE, KANSAS.

GAS-GENERATING OIL-BURNER.

1,224,854.

Specification of Letters Patent. Patented May 1, 1917.

Application filed September 18, 1916. Serial No. 120,670.

To all whom it may concern:

Be it known that I, CARL CHARLES, a citizen of the United States, residing at Rosedale, in the county of Wyandotte and 5 State of Kansas, have invented certain new and useful Improvements in Gas-Generating Oil-Burners, of which the following is a specification:

This invention relates to gas generating 10 oil burners, and has for its object to produce an efficient and inexpensive burner for use in heating stoves, furnaces and the like. A further object is to produce a burner of simple and compact construction which can 15 be easily placed in or removed from the combustion chamber of a stove or furnace.

With these objects in view the invention consists in certain novel and peculiar features of construction and organization of 20 parts as hereinafter described and claimed; and in order that the invention may be fully understood reference is to be had to the accompanying drawing, in which:

Figure 1, is a top plan view of a burner 25 embodying the invention.

Fig. 2, is a section taken on the line II—II of Fig. 1.

In the said drawing, 1 is a shallow pan which may be of circular form as shown or 30 of any other suitable or preferred configuration, and said pan is adapted to rest upon the grate or other support of a stove or furnace. Preferably the pan is provided with a number of depending or supporting lugs or 35 feet 2 and with a central opening 3. It is also provided with a lining 4 of asbestos or equivalent absorbent non-combustible material.

Arranged horizontally at a suitable 40 height above and centralized with respect to the pan is a generator 5, which conforms preferably in contour to the pan, and the space encircled by the generator is closed by a plate or web 6 preferably cast with the 45 generator, said plate or web constituting the top of a mixing chamber hereinafter more particularly referred to.

At diametrically opposite points the generator is provided with tubular nipples 7 and 8, the same being internally threaded to 50 respectively receive elbow pipes 9 and 10, elbow 9 being screwed upon the upper end of a vertical pipe 11 connected by an elbow 12 to an oil supply pipe 13, leading from an 55 oil tank, not shown. The oil may flow from

the oil tank through the force of gravity or may be forced to flow by the use of compressed air or otherwise, and pipe 13 will be controlled by a needle valve, not shown, whereby the flow of oil may be regulated and controlled. As the use of an oil supply 60 tank and a regulating valve is not new in this class of appliances, neither have been shown. The pipe 13 contains a filter 14 to filter the oil before it reaches the burner proper, and said filter will also serve as an obstruction to back flow of oil or gases when pressure is produced in the generator, in order that the flow of gas to the mixing 65 chamber hereinbefore referred to, shall be 70 steady and uniform and without pulsation.

The filter 14 preferably consists of fine wire gauze rolled to cylindrical form and fitted snugly in pipe 13.

Extending vertically downward from and 75 secured to elbow 10 is a pipe 15 and said pipe is connected by an elbow 16 to a horizontal pipe 17 overlying and slightly spaced from the pan 1, and screwed on the inner end of 80 said pipe 17 and located vertically below the center of the plate or web 6 is T-coupling 18, the same resting upon the pan over opening 3 thereof, and in order to secure the coupling to the pan a threaded reducing 85 plug 19 is screwed into the coupling and extends down through opening 3 of the pan and is engaged at its lower end by a cap nut 20 which thus effects the clamping of the coupling firmly to the pan.

The upper end of the coupling is provided 90 with a reducing plug 21 and screwed upon the upper end of said plug is a gas tip 22, said tip having a fine jet orifice 23 in its center through which oil can flow slowly 95 and vapor can be discharged forcibly under pressure developed in the generator.

The generator is provided with a depending flange 24 upon which is fitted tightly with a gas tight relation a cylindrical burner head 25, and depending centrally from and communicating with the burner head is a mixing tube 26. The burner head is provided with a series of jet orifices 27 below the flange 24, and to secure said head in position it is provided with outwardly projecting lugs 28 fitting against the lower sides of nipples 7 and 8 and secured to said nipples by screw bolts 29. Assuming that it is desired to operate the burner, the controlling valve will be opened to permit oil to 105 110

flow through the supply pipe to the generator, and thence from the latter to the coupling 18 and overflow through the orifice 23 down into the pan upon which it will 5 quickly spread owing to the absorbent character of the lining of the pan. When the pan is sufficiently charged with oil, the operator closes the controlling valve and drops a lighted match or paper into the pan. This 10 ignites the oil which may be coal oil or distillate or any other oil sufficiently light to flow readily. The flames from the burning oil will rise and envelop the burner head and generator and the adjacent portions of the 15 pipes connected thereto and soon raise said parts to vaporizing temperature. This condition will be apparent to the operator by a change in the color of the flame, that is to say the initial yellow or red flame produced 20 by the burning oil will give place to a blue flame issuing from the jet orifices 27, owing to the fact that the oil will collect in the bottom of the generator 5 and will be vaporized and the vapor will force its way to the 25 coupling 18 and be forcefully ejected through the orifice 23 up through the mixing tube 26 into the mixing chamber of the burner head. In this passage the vapor will draw air through the mixing tube into the 30 mixing chamber, and the mixed air and vapor will issue from the orifices 27 as a combustible gas. When the color of the flame changes as explained, the operator will immediately reopen the controlling valve to 35 permit the oil to flow from the tank to the burner, which oil when it attains approximately the level of the top of pipe 11, will be converted into vapor and thence flow through the generator and from the same 40 to the coupling 18 and be forcefully discharged up through the mixing tube into the mixing chamber, drawing air into the mixing chamber as explained. The gas thus produced is discharged as explained from 45 the orifices 27, the length of the flames being determined by the quality and quantity of the oil supplied, it being apparent that as long as the controlling valve is open the heater will operate, and that it will maintain 50 the upper part of the device at vaporizing temperature.

From the above description it will be apparent that I have produced a device of the character described, possessing the features 55 of advantage enumerated as desirable, and I wish it to be understood that while I have illustrated and described the preferred embodiment of the invention I reserve the right to make all changes properly falling within 60 the spirit and scope of the appended claims.

I claim:

1. A gas generating oil burner, comprising a pipe line terminating in a tip provided with an orifice for discharging upwardly, said pipe line embodying two vertically disposed portions at opposite sides of and spaced from said tip, a pan underlying said vertically disposed portions of the pipe line and the discharge end thereof and secured in fixed relation to the latter, a circular generator forming a part of the pipe line and interposed between and connected at diametrically opposite points to the upper ends of the vertically-disposed portions of the pipe line and centralized with respect to and located in a higher plane than said tip; 80 said circular generator having a central imperforate portion or web and a depending circular flange, and a cylindrical burner head fitting with a gas-tight relation around and firmly secured to said flange and provided in a lower plane than the latter with a horizontal series of radial orifices and with a depending mixing tube terminating above and centralized with respect to said tip. 90

2. A gas generating oil burner, comprising a pipe line terminating in a tip provided with an orifice for discharge upwardly, said pipe line embodying two vertically disposed portions at opposite sides of and spaced from said tip, a pan underlying said vertically disposed portions of the pipe line and the discharge end thereof and secured in fixed relation to the latter, a circular generator forming a part of the pipe line and interposed between and connected at diametrically opposite points to the upper ends of the vertically-disposed portions of the pipe line and centralized with respect to and located in a higher plane than said tip; 95 said circular generator having a central imperforate portion or web and a depending circular flange, a cylindrical burner head fitting with a gas tight relation around said flange and provided in a lower plane than the latter with a horizontal series of radial orifices and with a depending mixing tube terminating above and centralized with respect to said tip, lugs extending outward from the burner head at opposite sides thereof and screws securing said lugs firmly to the generator. 110

In testimony whereof, I affix my signature, in the presence of two witnesses.

CARL CHARLES.
